UNITED STATES PATENT OFFICE

FREDERICK STONE, OF LOS ANGELES, CALIFORNIA, ASSIGNEE TO DOHENY-STONE DRILL CO., OF LOS ANGELES, CALIFORNIA, A CORPORATION OF DELAWARE

SAND REEL

Application filed December 15, 1930, Serial No. 502,881. Renewed July 5, 1932.

This invention has to do generally with hoisting machinery, and is of a type particularly well adapted for application to sand reels employed in the drilling and operation 5 of oil wells. Accordingly, I shall describe my invention as applied to a hoist put to this particular use, though it will be understood this is not to be considered limitative on the invention.

10 During the drilling and operation of oil wells it often becomes necessary to lower and raise relatively light implements through the well bore. These implements are such that it requires only a relatively light line 15 to handle them, because of which, together with the fact that they are usually to be lowered and raised with relative rapidity and yet under perfect control of the operator, it has become customary to use what are termed 20 sand reels for such operations. Sand reels are of relatively light construction and are adapted to be driven independently of the relatively heavy hoisting drums used for raising and lowering drilling tools, casing, etc., these heavy drums and their operating mechanism not being adapted efficiently to perform relatively light, rapid and delicate hoisting and lower operations, as is well understood by those skilled in the art.

25 For instance, in the operation of bailing a well it is often necessary repeatedly to lower and raise a relatively light bailer, and it will be seen that the usual heavy hoist or draw-works is not adapted to perform such a task 30 efficiently. This is particularly true since it is often necessary to reciprocate the bailer through relatively short strokes after it has reached working position in the well, and the heavy hoisting equipment of the draw works 35 is not designed for such delicacy and rapidity of operation.

40 Usual sand reels are operated by bodily swinging a friction wheel into and out of frictional engagement with a constantly driven drive wheel. This method of control is neither safe nor fully efficient. It does not permit the delicacy of control desirable, except in the hands of particularly skilled operators, for if any parts be slightly out of 45 adjustment or unduly worn, the slightest

bodily movement of the friction wheel may mean, the difference between a full speed drive of the reel or complete release of the load. Not only are the parts subject to excessive and uneven wear and therefore require 55 frequent adjustment and replacement, but the entire drive system is not well adapted to take care of suddenly increased loads. For instance, if the bailer happens to hang up 60 momentarily during the hoisting operation, it frequently happens that the line is snapped, since the operator has no warning and cannot respond quickly enough to release the driving engagement in time to prevent line breakage.

65 It is therefore among the objects of my invention to provide novel and dependable means for controlling a sand reel with extreme delicacy, that is, a control which will permit great nicety of adjustment in the lowering and hoisting speeds, enabling the 70 operator to regulate such speed with dispatch, precision and in exact conformance with the demands of the task he has in hand.

75 All this is accomplished with a driving arrangement in which the wear on and necessity of adjustment of parts are reduced to a minimum. Furthermore, in the event of a sudden increase in load, the drive connection yields in a manner to prevent line 80 breakage.

85 It is a further object of the invention to render the sand reel and its control mechanism entirely self-contained, that is, the novel means I provide for regulating the hoisting speed so it may be at any point between zero 90 and the high speed limit of the driving means, is all contained within the main body of the hoisting apparatus. This is of obvious advantage from the standpoints of compactness, safety and general efficiency.

95 I provide a novel clutch for regulating the hoisting speed of the reel, this clutch being in the form of planetary gearing, a particularly advantageous feature residing in the fact that the planetating elements of this system are carried by and within that member, in this case a drum, to which is applied the controlling clutch brake band.

100 It is a further object of the invention to provide a novel and particularly efficient

manner of mounting the various elements of the planetary clutch system on the main shaft of the sand reel and of operatively associating them with the sand reel, proper. These 5 points, as well as other features of novelty and objects of the invention will be apparent from the following detailed description.

Figure 1 is a side elevation of a sand reel embodying my invention, parts of the structure being shown broken away and in section 10 to illustrate certain details of construction. That part of the frame which is broken away illustrates sections taken on lines 1-1 of Figs. 3 and 4;

15 Fig. 2 is a top plan view of Fig. 1; Figs. 3 and 4 are sections on line 3-3 and 4-4, respectively, of Fig. 1, slightly reduced in scale; in both cases the drums being shown diagrammatically to eliminate the 20 showing of their contained mechanism; which is unnecessary to an understanding of these views.

Fig. 5 is an enlarged section on line 5-5 of Fig. 2; and

25 Fig. 6 is a side elevation of the planetary drum in detached condition.

While the supporting structure of my sand reel is in no way controlling on my invention, I have illustrated a particularly sturdy 30 frame support made up of sills 10, end cross bars 11, cross bars 12 spaced slightly from bars 11, and intermediate cross bar 13. Welded to bars 12 are vertical end plates 14 which are braced by plates 15 and to which are 35 welded uprights 16, preferably in the form of channels. Bolted to channels 16 are bearings 17 which support the main shaft 18 of the reeling drum or spool generally indicated at S. Bearings 17 also take the end thrust 40 of shaft 18 and thus hold it against longitudinal play.

The spool portion S of the sand reel may be of any desired type. I have here shown a standard form of reel made up of drum 45 sections 19 and 20 which are clamped between flanges 21 by through bolts 22, the latter extending through the two hubs 23 provided at opposite ends of the spool. These hubs, in turn, carry flanges 24 which 50 are bolted at 25 to the outer flanges 21. The hubs are keyed at 26 to shaft 18, it following that spool S and shaft 18 always revolve as one.

On the opposite end of shaft 18 and keyed 55 thereto at 27 is a drive sleeve 28. Sleeve 28 has at one end a head or flange 29, while the opposite end is threaded as at 30. Bolted to one side of flange 29 is the web 31 of brake drum 32. The same bolts 33 which hold said 60 drum to flange 29 are conveniently used to hold bevel ring gear 34 to the opposite side of flange 29. This ring gear is a part of the planetary clutch or driving system, as will be later made apparent. Due to the keying 65 of sleeve 28 to shaft 18, it will be seen that

brake drum 32, gear 34, and spool S are always adapted to rotate as one with shaft 18. Accordingly, the drive to the spool from the planetary system and the braking of the spool to control its unreeling speed may be 70 accomplished through the single drive sleeve 28. Due to the rigid interconnection of all these parts through shaft 18, it will be seen that, in effect sleeve 28, brake drum 32 and gear 34 may be considered a part of spool S, and that therefore the direct mounting of 75 said drum, sleeve and gear on said spool lies within the scope of my invention, considered in its broader aspects.

With the exception of gear 34, all elements 80 of the planetary drive or clutch, generally indicated at P, are mounted for bodily rotation about shaft 18. The planet gear carrier 36 of clutch P is in the form of a flanged drum having an external brake-band receiving face 37. The rim 38 and hub 39 of drum 36 are connected by spaced webs 40, the hub carrying an internal bearing liner 41a whereby the drum is mounted for smooth 85 rotation about shaft 18. At diametrically opposite points, rim 38 and hub 39 are provided with opposed bosses 41 and 42, respectively, these bosses having alined bores 43 and 44, respectively. Planet gears or bevel pinions 45 are held between bosses 41 and 42 by stationary stub shafts 45a, said shafts being held against longitudinal displacement at one end by their engagement with bearing sleeve 41a and at their other ends by removable plugs 46 which are threaded into bores 100 43. Bearings 47 provide for the proper rotational mounting of the pinions about the stub shafts. Gears 45 are held in mesh with ring gears 34 by means which will be described later.

Mounted on and for rotation about sleeve 28 is a bevel ring gear 48 which has the same diameter and tooth characteristics as ring gear 34. Gears 48 and 34 are, of course, axially alined and are in spaced opposition, with 110 gears 45 and the web of carrier 36 between them. Gear 48 has an elongated hub 49 in the bore of which is secured a bearing sleeve 50. An oil pocket 51 is provided in hub 49 to which pocket oil is fed from the exterior through passageway 52' and from which pocket oil is fed through passageway 52 between sleeve 50 and sleeve 28. At the outer end of hub 49 is provided a thrust bearing 53, a keeper ring 54 being threaded on drive sleeve 28 at 30 to engage the outer end of this thrust bearing and thus serving to hold gears 48, 45 and 34 in mesh and hence holding clutch drum or planet gear carrier 36 against longitudinal displacement along 115 sleeve 28.

A drive sprocket 55 is bolted at 56 to flange 57 on hub 49. Hoisting power is applied to sprocket 55 through a chain connection (not shown) with any suitable prime 120

5 mover (not shown) the prime mover serving to rotate gear 48 constantly in a given direction, the direction being such that it will wind line L upon spool S when the planetary clutch is in driving condition, as will be described.

10 Before describing the operation of the planetary gearing, I will first describe the selectively operable means for applying braking force to clutch drum 36, whereby the drive through the planetary from the sprocket to the spool is accomplished, and the means for applying braking force to brake drum 32. Spaced brackets 60 and 61 are secured to one of the sills 10 at 62 and 15 63, respectively, these brackets serving both to support the operating rock shaft 64 and to anchor the dead end of brake bands 65 and 66, these bands being applied to drums 36 and 32, respectively, in the usual manner. 20 The anchoring is accomplished through tension rods 67 and 68 which are clipped to bands 65 and 66, respectively, in the usual manner illustrated and are hooked at their lower ends into brackets 60 and 61, respectively, as clearly shown in Fig. 1. Fixed to rock shaft 64 are downwardly and upwardly extending crank arms 69 and 70, respectively, there being a usual draw-bar connection 71 between the free end of band 65 25 and crank 69, and draw-bar or link connection 72 between the free end of band 66 and crank 70.

30 Rock shaft 64 extends to the right hand end of the supporting frame, as viewed in Figs. 1 and 2, having bearing at 73 in one of the cross bars 12 and terminating in an angular extension forming the operating or swing lever 74. When lever 74 is in an upright position, (dot-dash lines in Figs. 3 and 4) cranks 69 and 70 are in the positions of Figs. 3 and 4, respectively, bands 65 and 66 then being in the loose or unapplied condition shown in these figures. If lever 74 be swung to the right (Fig. 3) shaft 64 is rotated in a clockwise direction causing a constriction of band 65 about drum 36 and further loosening band 66 from about drum 32. If lever 74 be swung to the left, as viewed in Fig. 4, shaft 64 is rotated in a counter-clockwise direction, thus 35 serving to constrict band 66 about drum 32 and further loosening band 65 with respect to drum 36. Thus, by manipulation of the single lever 74, the brake bands may be selectively applied to their respective drums. 40 and, of course, by varying the extent of lever-swing, varying degrees of braking pressure may be applied to either of the drums.

45 In describing the operation of the device, let us assume that we are hoisting at full speed. To bring this about, lever 74 will have been swung sufficiently to the right in Fig. 3 to constrict clutch band 65 tightly about drum 36 so said drum is held against rotation. Sprocket 55 is being rotated constantly in a given direction by the prime

50 mover, thus rotating ring gear 48 in said given direction. Since shafts 45a are held from bodily rotation about shaft 18, the drive of gear 48 will be transmitted fully through pinions 45 to ring gear 34, though the direction of rotation of gear 34 will be opposite that of gear 48. Gear 34 thus drives spool S in a "reeling-in" or hoisting direction, the drive from the gear to the spool being accomplished through drive sleeve 28, shaft 18 and 55 hubs 23.

If it be desired to decrease the reeling speed, it is only necessary for the operator to relieve the pressure on lever 74 to loosen band 65 slightly and thus allow drum 36 to slip, whereupon said drum with its gears 45 will planetate slightly and correspondingly reduce the driving effect imparted to gear 34 and hence to the spool. Of course, the looser the band 65, the slower will be the reeling 60 speed of spool S. When lever 74 is moved to an upright or neutral position, carrier 36 rotates freely about shaft 18, the gears 45 thus planetating freely about gear 34, and no drive will be imparted to gear 34 and spool S. On 65 the other hand in picking up a load the planetary clutch described enables a very gradual pick-up, if that be desired, this effect being gained by applying a gradually increasing amount of constricting force to 70 band 65. If it be desired to secure rapid acceleration, it is only necessary for the operator to apply greater braking force to drum 65 by proper manipulation of lever 74. In fact, between zero reeling speed and maximum reeling speed, as determined by the highest speed to be accomplished when drum 36 is held stationary, the operator has it 75 within his power to secure any one of an infinite number of speeds by the simple adjustment of the operating lever. This is true both during acceleration or deceleration, from one to the other of which he is free to turn at any stage of the operation by merely adjusting band 65 to vary the resistance to rotation of carrier 36. 80

85 While the clutch is thus of a very sensitive nature as far as its controlling effect is concerned, it is very sturdy, compact and efficient. The nature and arrangement of parts 90 are such that uneven and excessive wear thereof is reduced to a minimum, thus avoiding frequent adjustment and replacement. Furthermore, in the event the load is suddenly increased, as by hanging up of the line-supported tool, the planetary carrier may 95 slip with relation to its braking band, and thus avoid line-breakage as well as damage to the hoisting apparatus.

100 During the lowering-away operation, spool S and hence gear 34 are necessarily traveling in the direction opposite that followed when they are being driven through the planetary from sprocket 55, but this movement of the reel is allowed even though the 105

sprocket and gear 48 are still being rotated in their driving direction, since carrier 36 is then free to rotate about shaft 18 and gears 45 are freely planetatable, this movement 5 compensating for all differences in speed and direction of rotation between gears 34 and 48.

It will be evident from an inspection of Fig. 4, that if it be desired to check or stop the unreeling movement of spool S, it is 10 merely necessary to swing lever 74 to the left, as viewed in this figure, to constrict band 66 about drum 32, it having been explained that said drum and said spool are both keyed, in effect, to the one shaft 18. Of course, by 15 varying the swinging pressure exerted on lever 74 the braking effect of band 66 on drum 32 may be varied to check the rotation of the spool as desired.

It will be seen that since both clutch band 20 65 and brake band 66 are controlled from the single lever 74, it is a very simple matter for the operator to control with great nicety either the reeling or unreeling of the spool line, and that he can shift said lever to change 25 instantly from one effect to the other. This is a matter of great convenience, and sometimes of necessity, in performing certain sand line and other operations, as is well understood by those skilled in the art.

While I have shown and described one 30 specific embodiment of my invention, it will be understood that various changes in design, structure and arrangement may be made 35 without departing from the spirit and scope of the appended claims.

I claim:

1. In a device of the character described, 40 a shaft, a reeling drum keyed to said shaft, a driving sleeve keyed to said shaft, a ring gear fixed to said sleeve, a second ring gear mounted on said sleeve for rotation thereabout, said second ring gear being in spaced opposition to the first mentioned ring gear, a drive sprocket on the second ring gear, a 45 planet gear carrier having an external drum face and mounted on said sleeve for rotation thereabout, said carrier being positioned between said ring gears, planet gears carried by said carrier and held thereby in mesh with 50 said two ring gears, a constrictable brake band about said drum face, and means for constricting said band.

2. In a device of the character described, 55 a shaft, a reeling drum keyed to said shaft, a driving sleeve keyed to said shaft, a ring gear fixed to said sleeve, a second ring gear mounted on said sleeve for rotation thereabout, said second ring gear being in spaced opposition to the first mentioned ring gear, a 60 drive sprocket on the second ring gear, a planet gear carrier having an external drum face and mounted on said sleeve for rotation thereabout, said carrier being positioned between said ring gears, planet gears carried by 65 said carrier and held thereby in mesh with

mesh with said two ring gears, a constrictable brake band about said drum face, means for constricting said band, a brake drum fixed to said sleeve, a constrictable brake band about said brake drum, and means for constricting said band. 70

3. In a device of the character described, 75 a shaft, a reeling drum keyed to said shaft, a driving sleeve keyed to said shaft, a ring gear fixed to said sleeve, a second ring gear mounted on said sleeve for rotation thereabout, said second ring gear being in spaced opposition to the first mentioned ring gear, a drive sprocket on the second ring gear, a planet gear carrier having an external 80 drum face and mounted on said sleeve for rotation thereabout, said carrier being positioned between said ring gears, planet gears carried by said carrier and held thereby in mesh with said two ring gears, a constrictable brake band about said drum face, a 85 brake drum fixed to said sleeve, a constrictable brake band about said drum, and means operable to constrict said bands selectively. 90

4. In a device of the character described, 95 a shaft, a reeling drum keyed to said shaft, a driving sleeve keyed to said shaft, a ring gear fixed to said sleeve, a second ring gear mounted on said sleeve for rotation thereabout, said second ring gear being in spaced 100 opposition to the first mentioned ring gear, drive applying means on the second ring gear, a planet gear carrier mounted on said sleeve for rotation thereabout, said carrier being positioned between said ring gears, planet gears carried by said carrier and held thereby in mesh with said two ring gears, and means for regulatably checking rotation 105 of the carrier as set up by rotation of said second ring gear.

5. In a device of the character described, a shaft, a reeling drum keyed to said shaft, a driving sleeve keyed to said shaft, a ring gear fixed to said sleeve, a second ring gear mounted on said sleeve for rotation thereabout, said second ring gear being in spaced 110 opposition to the first mentioned ring gear, drive applying means on the second ring gear, a planet gear carrier mounted on said sleeve 115 for rotation thereabout, said carrier being positioned between said ring gears, planet gears carried by said carrier and held thereby in mesh with said two ring gears, means for regulatably checking rotation of the carrier as set up by rotation of said second ring gear, and brake means applied to said sleeve. 120

6. In a device of the character described, a shaft, a reeling drum keyed to said shaft, a driving sleeve keyed to said shaft, a ring gear fixed to said sleeve, a second ring gear mounted on said sleeve for rotation thereabout, said second ring gear being in spaced opposition to the first mentioned ring gear, drive applying means on the second ring gear, 125 and brake means applied to said sleeve. 130

a planet gear carrier mounted on said sleeve for rotation thereabout, said carrier being positioned between said ring gears, planet gears carried by said carrier and held there-
5 by in mesh with said two ring gears, means for regulatably checking rotation of the carrier as set up by rotation of said second ring gear, brake means applied to said sleeve, and means operable to actuate said checking
10 means and said brake means selectively.

In witness that I claim the foregoing I have hereunto subscribed my name this 28th day of November, 1930.

FREDERICK STONE.
